UNITED STATES PATENT OFFICE.

JOSEPH B. HOLDEN, OF SYRACUSE, NEW YORK, ASSIGNOR TO REMINGTON TYPE-WRITER COMPANY, OF ILLION, NEW YORK, A CORPORATION OF NEW YORK.

TYPEWRITING MACHINE.

Application filed September 8, 1923. Serial No. 661,618.

My invention relates to carriage feeding or escapement mechanism for typewriting machines, and its object is to provide new and improved mechanism of the character stated. More specifically, the object of my invention is to improve in certain respects the escapement mechanism of E. E. Barney disclosed and claimed in his application Sr. No. 659,116 filed Aug. 24, 1923, my improvements resulting in increased accuracy of operation of the escapement mechanism.

To the above and other ends which will hereinafter appear, my invention consists in the features of construction, arrangements of parts, and combinations of devices hereinafter described and particularly pointed out in the claims.

In the accompanying drawings which illustrate the preferred form of my invention applied to a Smith Premier No. 60 typewriting machine,

Figure 1 is a fragmentary side elevation partly in section showing the train of connections between the key operated universal bar and the escapement dog rocker, together with associate parts.

Figure 2 is a fragmentary rear elevation showing some of the parts of Fig. 1.

Figure 3 is a view corresponding to Fig. 1 but showing the parts in operated positions.

Figure 4 is an enlarged detail view, and

Figure 5 is a side elevation partly in section showing the mounting of the spring for restoring the universal bar and oscillator.

The Smith Premier No. 60 typewriter employs a set of type bars arranged in an arc of a circle and normally horizontally disposed below the platen 1, with the front face whereof said type bars co-operate. One of the middle type bars of the set is shown in the present case, said type bar being numbered 2. The set of type bars are mounted on a common arcuate pivot wire 3 which is supported on a vertically disposed segmental type bar support 4 formed with radial slots, in each of which one of the type bars is arranged and guided. Rigid with the segment proper is a supplemental or guide frame 5, the segment 4 and the frame 5 being adapted to be shifted vertically on the main frame of the machine to change case. The lower case position of the segment 4 and frame 5 is illustrated in full lines in Fig. 1 and the upper case position by

dotted lines, key operated devices not shown herein being employed to shift the segment and the frame downward for upper case. At their free ends the type bars are supported on a rest 6 which is connected with the shiftable segment and frame and shifts downward with them, the relationship of the type bars on their support consequently remaining the same in both shift positions. The heel of each type bar is connected by a rearwardly extending link 8 with the upper end of a lever 9, the parts 8 and 9 being elements of the key operated train for actuating the type bar. Close to its pivot 3 each type bar is provided with a contact face 2^a which is adapted to co-operate with the front edge of a vertically disposed curved or arcuate universal bar 10 arranged in an arcuate groove indicated at 11 formed in the rear face of the type bar segment. Guide devices for the universal bar comprise a pin 12 carried by an extension 13 from the universal bar and engaging in a guide opening 14 in the segment. At its sides, the universal bar 10 is provided with rearwardly extending arms 15, each pivotally connected at 16 with the forked or bifurcated upper end portion of a crank arm 17, said crank arms extending upward from a rock shaft 18. The arms 15 fit loosely between the bifurcations in the arms 17, each pivotal device or pin 16 bridging the associate fork and passing loosely through the arm 15. The rock shaft 18 is pivoted at its ends on coned screw pivots 19 supported by arms 20 secured to the frame member 5, check nuts 21 holding the screw pivots in adjusted positions on said arms. Rising from one end portion of the rock shaft 18 is an arm 22 carrying at its upper end a lateral screw 23 to which is secured the rear end of a coiled spring 24. The front end portion of said spring is anchored to the part 5, preferably in the following manner, said spring has secured within it a flanged nut 25 which receives a long screw 26 that projects rearward through an opening in the part 5 (Fig. 5). The head 27 of the screw 26 is adapted to slide in a hole 28 in the segment, the rear end of said hole being reduced so as to prevent passage therethrough of the head 27 while affording free movement of the shank of the screw. The construction is such that the tension of the spring 24 may readily be varied by applying

ing a tool to the nick of the screw through the hole 28 and turning the screw in or out to move the nut 25 longitudinally thereof thus stretching or compressing the spring 24 as may be desired. It will be understood that the universal bar frame 10, 15 and the oscillator or support 17, 18 participate in the case shifting movements of the type bars, the segment 4 and the member 5, as indicated by dotted lines in Fig. 1.

Instead of connecting the push link or connector directly with a rigid arm on the rock shaft of the oscillator as in the application of Barney aforesaid, I provide an improved form of connection which has the advantage of affording fine adjustments, a feature which has been found highly desirable in practice. In carrying out this part of my invention there is provided an arm 29 which is fixed to or formed integrally with the rock shaft at about its middle and extends upward and rearward therefrom terminating in a rearward horizontally disposed extension 29^a. Pivoted supported on the rear end of this extension as by a loose rivet 30 is an angular plate 31 formed with a downward extension 32 provided with an arcuate slot indicated at 33 and struck from the pivot 30 of the plate 31 as a center. The forward end of the plate 31 carries a stud or headed pin 34. The slot 33 receives a headed screw 35 which is threaded into the side of the arm 29; a washer 36 being interposed between the head of the screw 35 and the face of the plate 31. It will be apparent that when the screw 35 is tightened, the plate 31 is held in fixed relationship with the arm 29, 29^a, and that by loosening the screw, the plate may be swung up or down on its pivot 30 thus varying the position of the stud or pin 34, after which the plate may be reclamped by the clamping means or screw 35. The adjustable stud 34 is engaged by the forked forward end of a link or connector 37 which extends rearward and is also forked or bifurcated at its rear end, the rear bifurcations co-operating with a circular groove 38 formed in a stud 39 fixed to and projecting laterally from the lower end of an arm or member 40 loosely mounted on a horizontal rock shaft 41 extending transversely of the machine. The ends of the rock shaft are countersunk to accommodate the coned ends of stationary pivot screws 42 that are threaded through lugs 43^a projecting rearward from a bracket 43 depending from the top plate 44 of the machine. The rock shaft supports a dog carrier or rocker angular in shape and comprising an upstanding arm 45, a barrel-like portion 46, and a forwardly extending arm or part 47. The barrel 46 is perforated to fit over the shaft 41 and has a boss or thickened portion 47 at its rear which receives a pair of set screws 48 that secure the dog rocker

to the rock shaft 41. It will be observed from Fig. 2 that the rocker abuts the arm 40 and that the stud 39 projects from said arm inward under the dog rocker. This gives a compact construction avoiding interference with certain of the tabulating mechanism of the machine. The member or arm 40 has an extension 40^a above the rock shaft 41, which extension is thinner than the lower part of the arm and is formed with a tapped hole which receives a threaded member or nut 49 having a hexagonal head 50 and abutting at its inner end against the rear face of a lug 45^a that is integral with the rocker arm 45, (Fig. 4). Passing loosely through a hole 51 in the nut 49 is a headed screw 52, the forward end of which is threaded through the lug 45^a. The screw holds the arm or member 40, 40^a, in fixed relationship with the rocker and prevents said arm from turning on the shaft 41. By loosening the screw 52 the nut 49 may be threaded in or out by means of a tool applied to the hexagonal head 50 and thereafter the screw 52 may be tightened to force the inner end of the nut to abut tightly against the lug 45^a. The construction affords means for varying the angular position of the arm or member 40, 40^a, on its shaft 41 thereby providing improved means for varying or adjusting the location of the stud 39 with which the push link or connector 37 engages. The forward end of the screw projects through and beyond a lug 45^a and acts in co-operation with a stop lug 53 on the bracket 43 to limit the forward movement of the dog rocker. Said rocker is maintained in its normal position against the usual stop by a restoring spring 54. Mounted on the rocker arm 45 and projecting above the same are escapement dogs 55 and 56 preferably of the construction disclosed in the Barney application aforesaid, said dogs co-operating with an escapement wheel 57 which is fragmentarily shown in Fig. 1, said wheel being connected with the carriage as in the Smith Premier No. 60 machine.

It will be understood that when one of the type bars is actuated to print, its contact face 2^a will towards the end of the stroke contact with the universal bar 10, moving it rearward and swinging the oscillator 17, 18 on its pivotal axis, causing the stud 34 to move rearward about the axis 19 of the oscillator. This movement of the stud will be transmitted through the link 37 to the stud 39 at the lower end of the arm 40 thus rocking the shaft 41 and actuating the dog rocker, swinging the arm 45 thereof forward until its screw 52 contacts with the stop 53. The parts at this time will be in the position illustrated in Fig. 3. On releasing the printing key the parts will be restored to normal position, the spring 24 assisting to restore the oscillator and the

universal bar, the dog rocker being restored by its spring 54. It will be observed that with the parts in lower case and normally related as shown by full lines in Fig. 1, the 5 link or connector 37 is inclined upward from the rear towards the front at an angle to the horizontal. When the shift key is actuated for upper case, the segment 4 and shift frame 5 together with the type bars, universal bar frame 10, 15 and oscillator 17, 18, 10 will be moved bodily downward to upper case position. As the stud 34 shifts downward, it will swing the link 37 downward about the stud 39 as a center, said stud not 15 being affected by the shaft. The shifted position of the link is illustrated in dotted lines in Fig. 1, the link being swung to an angle below the horizontal corresponding with that from which it started above the 20 horizontal. My improved construction affords means for adjusting the parts with great nicety so that this angular swing from above to below the horizontal may be accurately obtained. It will be apparent that 25 if the stud 34 is too high it may readily be lowered and reset by loosening the clamping screw 35 and swinging the plate 31 downward on its pivot 30 to a sufficient extent and then reclamping. On the other 30 hand if the stud is too low, it may be reset higher by swinging the plate upward and tightening the screw. Also it will be seen that the let-off of the escapement may be accurately adjusted by varying the setting 35 of the arm 40, 40^a and thus changing the relationship between the two studs 34 and 39, which are connected by the link 37, the timing depending upon the relationship 40 of the motion transmitting device or stud 34 to the stud 39 or device to which motion is transmitted.

It will be observed that by my present invention there is provided a driving member, namely, the oscillator 17, 18, a driven member, namely, the dog rocker element comprising the rocker proper and the part 40, and a link, as 37, directly connecting the driving and driven members, which members are relatively shiftable as when 45 the case shifting operation takes place, combined with adjustable means for insuring a substantially uniform transference of motion through the link in both case shift positions; and that in the present instance the 50 means aforesaid comprises the adjustable plate or link carrier 31 and means for clamping the same in different set positions.

Various changes may be made without departing from my invention.

60 What I claim as new and desire to secure by Letters Patent is:—

1. In a typewriting machine, the combination of a shiftable universal bar, a dog carrier independent of case shifting movements, connections between said universal

bar and said dog carrier comprising a link, means for varying the points of connection of said link with its associate parts, said means comprising a pivoted plate, and means for clamping said plate in invariable 70 positions.

2. In a typewriting machine, the combination of a shiftable universal bar, a dog carrier, independent of case shifting movements, connections between said universal 75 bar and said dog carrier comprising a link, means for varying the points of connection of said link with its associate parts, said means comprising a pivoted plate, and means for clamping said plate in invariable 80 positions, said plate and the end of the link connected to it participating in the shifting movements of the universal bar.

3. In a typewriting machine, the combination with a platen and a type bar segment relatively shiftable to change case, of a universal bar shiftable during the case shifting operation, a dog carrier independent of said case shifting operation, an oscillator supporting said universal bar and participating in case shifting movements, a link connecting said oscillator with said dog carrier, and adjustable means for insuring uniform action of said link in both case 90 shift positions.

4. In a typewriting machine, the combination with a platen and a type bar segment relatively shiftable to change case, of a universal bar shiftable during the case shifting 95 operation, a dog carrier independent of said case shifting operation, an oscillator supporting said universal bar and participating in case shifting movements, a part rigid with said dog carrier, a link pivoted at one end to said oscillator and at the opposite end to 100 said part, one end of said link shifting during the case shifting movement, and means for varying the normal position of said link so as to vary also its position at the end of the case shifting movement.

5. In a typewriting machine, the combination of a platen, a type bar segment shiftable to change case, an oscillator shiftable with said segment, a universal bar supported by said segment and by said oscillator and shiftable therewith, said universal bar being operative by the type bars of the machine and being adapted to actuate said oscillator, a dog rocker, a part rigid therewith, a link pivotally connected to said part at one end, 115 a link carrier with which the opposite end of said link is pivotally connected, and means for variably securing said link carrier in rigid relationship with said oscillator.

6. In a typewriting machine, the combination of a universal bar, a dog carrier, an oscillator to which said universal bar is connected, a stud adjustably supported on said oscillator, and a link engaging with said stud and connected to said dog carrier.

7. In a typewriting machine, the combination of a universal bar, a dog carrier, an oscillator to which said universal bar is connected, a plate pivoted on said oscillator, a device carried by said plate, means for affording adjustment of said plate, and a link connected both to said device and to said dog carrier.
8. In a typewriting machine, the combination of a universal bar, a dog carrier, an oscillator to which said universal bar is connected, a plate loosely pivoted to said oscillator, an engaging device carried by said plate, a clamping screw for variably clamping said plate to said oscillator, and a link engaging with said device and connected to said dog carrier.
9. In a typewriting machine, the combination of a curved universal bar, a type bar directly operating said universal bar, a pivoted oscillator by which said universal bar is supported, a slotted plate loosely pivoted to said oscillator, a stud on said plate, a clamping screw engaging the slot in said plate, a dog carrier, and a link pivoting on said stud and connected to said dog carrier.
10. In a typewriting machine, the combination of a universal bar, a rock shaft, a dog carrier secured to said rock shaft, an arm loosely pivoted on said rock shaft, means for adjustably securing said arm in fixed relationship with said dog carrier, and connections between said universal bar and said arm.
11. In a typewriting machine, the combination of a universal bar, a rock shaft, a dog carrier secured to said rock shaft, an arm loosely pivoted on said rock shaft, means for adjustably securing said arm in fixed relationship with said dog carrier, a stud on said arm, a pivoted oscillator supporting said universal bar, a stud on said oscillator, and a link having its ends engaging said studs.
12. In a typewriting machine, the combination of a universal bar; a rock shaft; a dog carrier secured to said rock shaft; an arm pivotally mounted on said rock shaft; means for adjustably securing said arm in fixed relationship with said dog carrier, said means comprising a nut threaded into said arm and adapted to abut against a part of said dog carrier, and a screw passing loosely through said nut and into said dog carrier for holding said nut in fixed position; and connections between said universal bar and said arm.
13. In a typewriting machine, the combination of a vertically disposed curved universal bar adapted to be operated directly by the type bars of the machine, a pivotally supported oscillator to which said universal bar is pivotally connected, a link extending rearward from the oscillator near its middle, a rock shaft, a dog rocker detachably secured to said rock shaft, an arm supported on said rock shaft at one side of said dog rocker, and an engaging device co-operating with said link, said engaging device being carried by said arm and extending inward beneath said dog rocker.

Signed at Syracuse, in the county of Onondaga, and State of New York, this 4 day of Sept., A. D. 1923.

JOSEPH B. HOLDEN.
